US0D1052580S

(12) **United States Design Patent** (10) **Patent No.:** **US D1,052,580 S**
(45) **Date of Patent:** **** Nov. 26, 2024**

(54) **DISPLAY DEVICE**

(71) Applicant: **Amazon Technologies, Inc.**, Seattle, WA (US)

(72) Inventor: **Wilfrido Loor Canizares**, San Francisco, CA (US)

(73) Assignee: **Amazon Technologies, Inc.**, Seattle, WA (US)

(**) Term: **15 Years**

(21) Appl. No.: **29/872,679**

(22) Filed: **Mar. 16, 2023**

(51) LOC (14) Cl. **14-02**

(52) U.S. Cl.

USPC **D14/341**

(57) **CLAIM**

The ornamental design for a display device, as shown and described.

DESCRIPTION

FIG. 1 is a top, front, right-side perspective view of a display device;

FIG. 2 is a bottom, back, left-side perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dashed broken lines depict portions of the display device form no part of the claimed design. The dot-dashed broken lines represent boundaries of the claimed design and form no part of the claimed design.

1 Claim, 8 Drawing Sheets
